(57) **CLAIM**

The ornamental design for a display screen portion with graphical user interface, as shown and described.

DESCRIPTION

This application incorporates herein by reference in its entirety U.S. Design patent application Ser. No. 29/561,177, which was filed on the same day by the same applicant, bearing the same title and listing the same inventors.

FIG. 1 is a front view of a display screen or portion thereof with graphical user interface showing a first embodiment of our new design;

FIG. 2 is a front view of a display screen or portion thereof with graphical user interface showing a second embodiment of our new design;

FIG. 3 is a front view of a display screen or portion thereof with graphical user interface showing a third embodiment of our new design; and,

FIG. 4 is a front view of a display screen or portion thereof with graphical user interface showing a fourth embodiment of our new design.

The outermost dot-dash broken line perimeter in FIGS. 1-4 illustrates a display screen or portion thereof and forms no part of the claimed design. The remaining broken lines, including all text features, illustrate portions of a graphical user interface and form no part of the claimed design.
